UNITED STATES PATENT OFFICE.

FRANK A. HILL, OF SAN LEANDRO, CALIFORNIA.

SULKY-PLOW.

SPECIFICATION forming part of Letters Patent No. 239,249, dated March 22, 1881.

Application filed November 5, 1880. (No model.)

To all whom it may concern:

Be it known that I, FRANK A. HILL, residing at San Leandro, in the county of Alameda and State of California, have invented 5 a new and useful Improvement in Sulky or Gang Plows, of which the following is a specification.

My invention relates to the means employed to adjust or change the height of the land- 10 wheel of a sulky or gang plow with reference to the furrow-wheel, as may be required, by the plows running at a greater or less depth.

My invention is illustrated by the accompanying drawing, in which the figure represents 15 a common gang or sulky plow, with the plows, tongue, and seat removed.

A and A' represent the iron beams to which the plows are attached.

B is an iron bolster, to which the axle C, hav- 20 ing the studs or arms D and D', is hinged. The function of the axle C, with its arms D and D', is to raise and lower the beams A and A' in the usual manner when it is rotated by means of the lever I.

25 Journalized on one end of the axle C is a bell-crank, E, having a spindle, on which the land-wheel K revolves. The said bell-crank E is connected to the lever F by the connecting-bar G. The said lever F is pivoted at its 30 lower end to the bolster B, at the point where the axle C, with its studs or arms D and D', is

attached. The said lever F may be held in any desired position by the segmental ratchet H. The bell-crank E is moved as may be desired by the lever F through the medium 35 of the connecting-bar G, thus raising or lowering the land-wheel K, so that the plows may run at any required depth.

It will be seen that the position of the said land-wheel K can be quickly changed by the 40 above-described means, while the axle C remains free to rotate, by means of the lever I, and raise and lower the plows. In other words, either of the levers F and I may be moved freely the length of its ratchet, while the other 45 is held at a fixed point, thus enabling the driver, without stopping his team or leaving his seat, to adjust his plows to any required depth of plowing.

Having thus described my invention, what I 50 claim, and desire to secure by Letters Patent, is—

The axle C, having the arms D D', and lock- 55 ing-lever I, in combination with the bolster B, carrying beams A A', and also pivoted on said arms, and with the lever F, bell crank E, connecting-link G, and wheel K, all as and for the purpose set forth.

FRANK A. HILL.
